UNITED STATES PATENT OFFICE.

PINCUS BURGER, OF NEW YORK, N. Y.

ELECTRIC-LIGHT FIXTURE.

984,536.

Specification of Letters Patent. Patented Feb. 21, 1911.

Application filed December 23, 1910. Serial No. 598,973.

To all whom it may concern:

Be it known that I, PINCUS BURGER, a citizen of the United States, and residing at New York, in the county of New York and State 5 of New York, have invented certain new and useful Improvements in Electric-Light Fixtures, of which the following is a specification, such as will enable those skilled in the art to which it appertains to make and 10 use the same.

This invention relates particularly to attachable and detachable metal shade holders for incandescent electric lamp sockets and especially to the means for connecting the 15 shade holder with said sockets, the object being to provide a simple and effective device of this class which may be easily and conveniently manipulated both in attaching and detaching the shade holder.

20 The invention is fully disclosed in the following specification, of which the accompanying drawing forms a part, in which the separate parts of my improvement are designated by suitable reference characters in 25 each of the views, and in which:

Figure 1 is a side view showing an electric lamp socket with a shade holder connected therewith and suspended therefrom; Fig. 2 a sectional view of said parts and 30 showing my improvement; and Fig. 3 a plan view of the shade holder detached from the socket and showing my improvement.

In the drawing forming part of this specification, I have shown at a an ordinary electric lamp socket provided with a depending tubular member a^2 , said depending tubular member being provided, as shown in Fig. 2, with an annular bead a^3 . I have also shown at b an ordinary shade holder with which 35 is detachably connected a shade c , the general form of said shade holder and the method of connecting the shade c therewith being the same as usual in this class of devices, and forming no part of my invention.

40 The shade holder b is provided at the top thereof with an annular neck piece or band b^2 into which the downwardly directed tubular member a^2 of the lamp socket a is adapted to be inserted, and said downwardly 45 directed tubular portion a^2 of the lamp socket a is of less diameter than the neck or band b^2 of the shade holder b . Passed through one side of said neck or band b^2 of the shade holder b is a screw d , the inner 50 end of which is rotatably connected with an

arc-shaped flat spring e placed within said neck or band b^2 and the length of which is approximately one hundred and eighty degrees. Directly opposite the screw d , the neck or band b^2 of the shade holder is provided with an inwardly directed lug or projection f which, in the form of construction shown, is formed integrally with said neck or band, but which may be formed on or connected with said neck or band in any 60 desired manner and at diametrically opposite points between the lug or projection f and the screw d , said neck or band is also provided with inwardly directed lugs or projections f^2 which also form keepers into and 65 through which the ends of the spring e are movable. In the form of construction shown, the keepers f consist of tongues formed on the top of the neck or band b^2 of the shade holder and bent inwardly and 70 downwardly, but said keepers may be formed on, or connected with, the neck or band b^2 in any desired manner, all that is necessary in this connection being that said keepers form inwardly directed lugs or projections 75 which operate in connection with the lug or projection f and the spring e to hold the shade holder b in connection with the lamp socket a as hereinafter described.

When the screw d is in the position shown 80 in full lines in Fig. 3, said position being the outermost position of said screw, the downwardly directed tubular member a^2 of the lamp socket a may be inserted into the neck or band b^2 of the shade holder b , as shown in 85 Fig. 2, and then by turning said screw d inwardly so that the spring e assumes the position shown in dotted lines in Fig. 3, and in full lines in Fig. 2, the said shade holder will be locked to the lamp socket, or to the 90 part a^2 thereof as will be readily understood, and as clearly shown in Fig. 2, and when it is desired to detach the shade holder, all that is necessary is to turn the screw d 95 back into the position shown in full lines in Fig. 3, after which the shade holder may be easily detached from the lamp socket, as will be readily understood. It will also be seen that with my improvement the shade holder is supported concentrically on the lamp 100 socket, or on the part a^2 thereof, said part a^2 of the lamp socket when the shade holder is connected therewith being concentric in the neck or band b^2 of the shade holder.

105 It will be understood that the screws g in 110

the base portion of the shade holder serve to hold the shade *c* in connection therewith, but as these features form no part of my invention, they are not shown and described in detail. I also, in practice, preferably locate the screw *d* midway between two of the screws *g*, as clearly shown in Fig. 3, but this is not an essential element.

Having fully described my invention, 10 what I claim as new and desire to secure by Letters Patent, is:—

1. The herein described means for connecting a shade holder with a lamp socket, said socket being provided with a downwardly directed tubular member having an annular bead, and said shade holder being provided with a neck or band portion of greater diameter than said tubular member, consisting of a screw passed inwardly 20 through one side of said neck or band portion, an inwardly directed lug or projection on said neck or band portion opposite said screw, and two inwardly directed lugs or projections on said neck or band portion at 25 diametrically opposite points and between said screw and said first named lug or projection, said last named lugs or projections forming keepers, and a plate spring rotatably connected with the inner end of said

screw and the ends of which are movable in 30 and through said keepers.

2. The herein described means for securing a shade holder to a lamp socket and for centering said lamp socket in said shade holder, said lamp socket being provided 35 with a downwardly directed tubular member having an annular bead, and said shade holder being provided in the top thereof with a neck or band portion, consisting of a plurality of inwardly directed lugs or projections on said neck or band, a screw passed inwardly through one side of said neck or band midway between two of said lugs or projections, said two lugs or projections being adapted to serve as keepers, and a 40 plate spring rotatably connected with the inner end of said screw and the ends of which are movable in and through said keepers.

In testimony that I claim the foregoing as 50 my invention I have signed my name in presence of the subscribing witnesses this 22nd day of December 1910.

PINCUS BURGER.
